GAME APPARATUS

Raymond F. Nekuda, Kansas City, Mo.

Application November 25, 1932
Serial No. 644,255

2 Claims. (Cl. 273—95)

My invention relates to improvements in game apparatus.

It relates particularly to a game apparatus in which an elongated projectile is adapted to be 5 tiltably supported on a suitable support, and while so supported being adapted to be struck by a club and hurled toward a distant target.

One of the objects of my invention is to provide novel means for tiltably supporting the projectile in a manner such that the projectile may 10 be adjusted to different radial positions so as to be projected in different aimed directions, novel means being provided for yieldingly holding the projectile supporting means in the position to 15 which it may be adjusted.

A further object of my invention is the provision of a novel target having compartments of different areas adapted to receive and hold a projectile none of the dimensions of which exceeds any dimension of any of said compartments.

Still another object of my invention is to provide a novel club for striking and hurling the projectile.

25 A further object of my invention is to provide a game apparatus of the kind described, which is simple, cheap, durable, and which is adapted to be collapsed into relatively small space for storage or transportation.

30 The novel features of my invention are herein-after fully described and claimed.

In the accompanying drawing, which illustrates the preferred embodiment of my invention.

Fig. 1 is a plan view of the apparatus disposed 35 in condition for use.

Fig. 2 is an elevation of the same.

Fig. 3 is an enlarged section on the line 3—3 of Fig. 2.

40 Fig. 4 is an enlarged side view, partly in vertical section and partly in side elevation, of the projectile supporting stand, shown partly broken away and in operative condition and supporting a projectile adapted for use therewith.

45 Fig. 5 is a plan view, partly broken away, of the supporting stand.

Fig. 6 is an under view of what is shown in Fig. 5.

Fig. 7 is a side elevation, partly broken away, of one of the legs of the stand.

50 Fig. 8 is an enlarged view of the upper end of one of the legs of the stand.

Fig. 9 is an enlarged side elevation of the projectile.

55 Fig. 10 is an enlarged end view of the projectile.

Similar characters of reference designate similar parts in the different views.

1 designates an elongated projectile, having tapering ends, preferably composed of wood, soft or hard rubber, or other suitable material, which 60 is adapted to be tiltably supported and hurled toward a target when struck by a club in a proper manner. 2 designates a club having mounted on one end portion a resilient covering comprising, preferably, a tube of soft rubber 3.

65 For supporting the projectile 1 in position for being struck by the club 2, there is provided a stand having a top 4, the under side of which is provided with a plurality of suitably disposed holes 5 adapted to have respectively removably 70 inserted into them the upper longitudinal split resilient ends of legs 6, the lower end of each of which has fitted into it a spike 7 adapted to be extended into the ground, when the stand is to be supported by the ground or to rest upon a floor, 75 carpet or sheet.

80 Radially adjustable on the top 4 is a projectile supporting member comprising, preferably a flat piece of wood 8 through which extends a vertical bolt 9, which also extends through the top 4 and has mounted on its lower end a nut 10.

85 Encircling the bolt 9 is a coil spring 11, the lower end of which bears against the nut 10, the upper end of the spring bearing against the under side of the top 4 with a pressure such that the member 8 will be pressed against the upper side of the top 4, so as to be yieldingly held in the radial position to which it may be adjusted on the top 4.

90 The upper side and front end of the member 8 is provided with means for tiltably supporting and retaining in an aimed position the projectile 1, such supporting means comprising, preferably a longitudinal groove 12, Figs. 4 and 5.

95 When the projectile 1 is to be hurled from the member 8, the projectile is disposed in the groove lengthwise thereof and, preferably projecting at its front end from the member 8. The latter is then adjusted to the desired position radially, and the front end portion of the projectile is 100 struck downwardly with the rubber covered portion 3 of the club 1. Such a blow will cause the projectile to be hurled in the aimed direction.

The target to be used with the projectile 1 comprises a plurality, three being shown in the 105 drawing, of flexible rings 13, 14 and 15, preferably consisting each of a piece of rope with the ends connected.

110 The rings are connected by radial cords 16 which serve the double function of retaining the

rings in spaced apart relation to each other, one within the other. To the under side of the rings 13, 14, and 15 is fastened a flexible sheet, such as canvas 17, which also serves to yieldingly hold the rings in spaced relation to each other. The compartments formed between the cords 16 may be designated by numerals of different values, such as "20" for the compartments between the outer ring 13 and the middle ring 14; "30" for the compartments between the middle ring 14 and the innermost ring 15, and "50" for the compartment in the ring 15.

The projectile 1 has no dimension greater than any dimension of any of the compartments between the rings, so that when the projectile is cast into any compartment it may be disposed therein without touching any one of the rings, in which case the rules of the game could provide an extra count for the shot.

In the playing of the game, the target is placed at a distance from the stand, and the player, adjusts the member 8 to what he considers is the proper angle, and then with the club projects the projectile toward the target. If properly shot, the projectile will alight on the sheet 17 in one of the compartments, and the shooter will be credited with the tally corresponding to the compartment containing the projectile, with an extra count in case the projectile is clear of any of the rings or cords 16.

After the game is finished, the legs of the stand may be withdrawn from the holes 5, the target folded or rolled, and these parts together with the club 2 and projectile 1 may be disposed together in small space for storage or transportation.

While but one projectile is shown in the drawing, it is obvious that as many of these may be employed as there are players, and they may be each distinguished from the others in any suitable manner, as by having different colors.

The player at times when striking downwardly against the projectile 1, accidentally hits the projectile at a point to the rear of the outer end of the grooved supporting member 8. To reduce the shock and possible breaking of the club in

such instances, the supporting member 8 is extended outwardly beyond the adjacent arcuate outer edge of the top 4, so that, if the projectile is struck over such projecting portion of the member 8 the latter will be tilted downwardly, which tilting movement will be resisted yieldingly by the spring 11. The latter thus effects the double function of holding the member 8 in its adjusted position and of yieldingly resisting downward tilting of the member 8 in case the projectile is accidentally struck on that portion which is over the projecting portion of the member 8, thus avoiding shock and possible damage to the apparatus.

I do not limit my invention to the structure shown and described, as many modifications, within the scope of the appended claims, may be made without departing from the spirit of my invention.

What I claim is:—

1. In a game apparatus, a support, a supporting member pivoted thereon on a vertical axis and having in its upper side a longitudinal groove extending to the outer end of said member, and adapted to be radially adjusted to different angles, resilient means normally holding said member against said support, and an elongated projectile movable sidewise vertically into and out of said groove and adapted to be extended outwardly beyond the outer end of said member and, when struck downwardly on said projecting portion, to be revolved and hurled out of said groove.

2. In a game apparatus, a support, a supporting member pivoted thereon on a vertical axis and extending at its outer end outwardly beyond said support, and having in its upper side a longitudinal groove extending to the outer end of said member, resilient means normally holding said member against said support, and an elongated projectile movable sidewise vertically into and out of said groove and adapted to be extended outwardly beyond the outer end of said member and, when struck downwardly on said projecting portion, to be revolved and hurled out of said groove.
